UNITED STATES PATENT OFFICE

2,009,858

TOY

Harry F. Riopelle, Ecorse, Mich.

Application December 14, 1933, Serial No. 702,317

5 Claims. (Cl. 124—14)

My invention relates to a new and useful improvement in a toy, and particularly a toy of the type where an article may be propelled through the air. The invention is especially adapted for use in connection with a toy airplane or similar article, which will serve to support itself for a short period of time in the air, when propelled therein.

It is an object of the present invention to provide an elastic propelling member, mounted on a suitable support, which will serve as a runway for the propelled object, and in which the elastic member is so fastened to the supporting member, as to prevent its interfering with the travel of the propelled member over the runway.

Another object of the invention is the provision in a device of this class of a supporting body having its front ends slotted for the reception of an endless elastic band and provided with means for engaging the band and preventing its detachment therefrom.

Another object of the invention is the provision in a toy airplane of a central rib or main body, having a laterally extending, wing forming portion, mounted thereon, and movable longitudinally thereof into various positions.

Other objects will appear hereinafter.

The invention consists in the combination and arrangement of parts hereinafter described and claimed. The invention will be best understood by a reference to the accompanying drawing, which forms a part of this specification, and in which,

Fig. 1 is a side elevational view of the invention with parts broken away and parts shown in section, and taken on line 1—1 of Fig. 2.

Fig. 2 is a top plan view of the invention with parts broken away, and parts shown in section, and taken on line 2—2 of Fig. 1.

Fig. 3 is a fragmentary bottom plan view of the supporting body.

Fig. 4 is a sectional view taken on line 4—4 of Fig. 2.

Fig. 5 is a fragmentary bottom plan view of a modified form of the supporting body.

Fig. 6 is a sectional view taken on line 6—6 of Fig. 5.

As shown in the drawing I provide a supporting body 7 in the nature of a plate or board, which serves as a runway for the propelled object. One end of the body 7 is reduced in width to provide a handle 8. Rockably mounted between lugs 9 and 10, which project downwardly from the body 7, is a beam 11, to one end of which is swivelly connected the pin 12, which slidably

projects through the opening 13 formed in the body 7. A spring 14 engages at one end in a pocket 15, formed in the beam 11, and at the other end in a pocket 16 formed in the handle portion 8. This structure provides a trigger mechanism which serves to lock the propelled object in position on the runway or body 7 and to release the same when desired.

I have illustrated the propelled object as comprising a toy airplane, embodying the central rib 10 or body 17, extending upwardly from the rear end of which is the rudder plate 18, and from the sides of which extend the elevating plates 19. The forward end of the body 17 is provided with a head or nose 20, which is of greater thickness 15 than the rear end of the body or rib 17, inasmuch as this body tapers. A notch 21 is formed in the under surface of the forward part of the rib or body 17 and adapted to engage the endless elastic band 22.

The forward end of the body or runway 7 is slotted as at 23. This slit extends inwardly a distance from the end edge, so as to provide the furcations 24 and 25. The lower furcation 25 is cut away to provide the opening 26, extending centrally of which is the tongue 27. This tongue is merely a part of the furcation 25, as the opening 26 is not of square formation, as the tongue extends inwardly from one side. In securing the elastic band on the body or runway 7, it is inserted in the slit 23 with the central portion thereof of below, so as to engage the under surface of, the tongue 27, as clearly shown in Fig. 1 and Fig. 3. The elastic is then brought up over the end, so that when engaged in the notch 21 with the propelled object in the position shown in Fig. 1, the rubber will be stretched taut.

As shown in Fig. 1 the spring 14 serves to normally retain the pin 12, pressed upwardly so as to project above the upper face of the body 7. When the beam 11 is rocked against the compression of the spring 14, the pin 12 may be withdrawn to a position so that it terminates below the upper surface of the body 7. A central rib or beam 17 is provided with a socket 28 into which the pin 12 may project to lock this body 11 in fixed position on the runway or body 7. It is in this position in the view shown in Fig. 1, and the elastic band 22 is under tension. It is obvious that upon rocking of the beam 11, 50 the propelled body will be drawn along the body 7 by means of the band 22, and propelled from this body 7 as a runway. Due to the method of fastening the elastic band to the body 7, it moves out of the path of the propelled body and will not 55

snap back into the path of the propelled body. Due to the inclined surface 29, the disengagement of the band from the notch 24 will be an easy and quick disengagement. It is also believed obvious that should the endless band 22 become worn or break, the same may easily and quickly be replaced with another band by a child or inexperienced person, without requiring the mutilation or marring of the body 7 in any manner. The band, when in use, is detachable at will by simply disengaging the same from the tongue 21.

As shown in Fig. 1 the body or rib 17 is provided with an elongated slot 30 through which projects the plate 31, which extends at opposite sides of the rib or body 17, to provide the airplane wings. This plate 31 fits in the slot 30 with a snug but not a tight engagement, and may be freely moved in the slot 30 to various positions longitudinally of the beam or rib 17. Spaced openings 32 are formed in the beam or rib 17, into which may be dropped or pressed a pin 33, which extends through an opening formed in the plate 31. By moving the plate 31 longitudinally of the body 17, the behavior of the body when propelled, may be varied and this body may be caused to go through different types of movements, such as whirling in a circle, looping the loop, etc. The plate 31 is so mounted that should it strike an object while being propelled, it will pivot on the pin 33, and thus the likelihood of damaging the wing forming structure or plate 31 is reduced to a minimum.

In Figs. 5 and 6 I have shown a slightly different form of attaching the elastic band 22 to the body or runway 7. In this form of attachment the forward end of the body or runway 7 is slit as at 23' to provide the furcations 24' and 25'. At the rear end of the slit 23' there are formed in the furcation 25' openings 34 extending into each of which, from the side of the body 7, is a slit 35 formed in the furcation 25'. In mounting the elastic band on the body 7 in this type of structure, the band is stretched over the bottom of the body and caused to enter the slits 35 and then drawn forwardly in the slit 23'. This type of structure is also quite efficient in effecting a propelling of the body to be propelled and maintaining itself clear of the body, as the propelled object leaves the runway 7.

While I have illustrated and described the preferred forms of construction, I do not wish to limit myself to the precise details of structure shown, but desire to avail myself of such variations and modifications as come within the scope of the appended claims.

Having thus described my invention what I claim as new and desire to secure by Letters Patent is:

1. In a toy of the class described; a run-way forming body slitted inwardly from one end

thereof between the upper and lower surface to form an upper and lower portion separated from each other except at their inner ends, the lower portion being cut away to provide an engagement portion; and an endless elastic band looped around said engagement portion and projected through said slit outwardly of the end of said body.

2. In a toy of the class described, a run-way forming body having one end slitted between the upper and lower surfaces to form an upper and a lower portion, said lower portion having an opening formed therein communicating with said slit; a tongue on said lower portion extending into said opening and terminating in spaced relation to the side of said opening; an endless elastic band looped around said tongue and projected through said slit outwardly of said end of said body.

3. In a toy of the class described, a run-way forming body having one end slitted between the upper and lower surfaces to form an upper and a lower portion, said lower portion having a pair of spaced openings formed therein and communicating with said slit, there being a slit formed in said lower portion extending from each of said openings outwardly to the side edges of said body; and an endless elastic band looped around the portion of said lower portion lying between said openings and projected through said first mentioned slit outwardly of said end of said body.

4. In a toy of the class described, a run-way forming body having one end slitted between the upper and lower surfaces to form an upper and a lower portion, there being formed in said lower portion a slit extending inwardly from each side edge thereof in communication with the slit between said upper and lower portions, said inwardly extending slits terminating in spaced relation to each other; and an endless elastic band looped around the part of said lower portion lying between the inner ends of said inwardly extending slits and projected between said upper and lower portions outwardly of said end of said body.

5. In a toy of the class described, a run-way forming body slitted inwardly from one end thereof between the upper and lower surfaces to form an upper and a lower portion, there being an opening formed in said lower portion, adjacent its inner end intermediate its edges, communicating with said slit; an engagement member carried by said body and directed cross-wise of said opening; and an endless elastic band inserted at one end through said slit and into said opening and looped around said engagement member, the opposite end projecting outwardly of said slit at the end of said body.

HARRY F. RIOPELLE.
